(57) CLAIM

The ornamental design for a toy ship, as shown and described.

DESCRIPTION

FIG. 1 is a left front perspective view of a toy ship showing my new design;

FIG. 2 is a right rear perspective view thereof;

FIG. 3 is a front elevational view thereof;

FIG. 4 is a rear elevational view thereof;

FIG. 5 is a top plan view thereof;

FIG. 6 is a bottom plan view thereof;

FIG. 7 is a right side elevational view thereof;

FIG. 8 is a left side elevational view thereof; and,

FIG. 9 is a right rear perspective view thereof, showing the roof, rear side, and doors on the right and left sides in an open state.

The broken lines illustrate portions of the toy ship that form no part of the claimed design.
